Attorneys PLLC(57) **CLAIM**

The ornamental design for a user interface housing, as shown and described.

DESCRIPTION

FIG. 1 is a front, right side perspective view of a user interface housing showing our new design;

FIG. 2 is a right side view thereof;

FIG. 3 is a left side view thereof;

FIG. 4 is a bottom, front perspective view thereof;

FIG. 5 is a top, front perspective view thereof;

FIG. 6 is a top, rear perspective view thereof; and,

FIG. 7 is a rear view thereof.

The broken lines in FIGS. 6 and 7 depict portions of the user interface housing that form no part of the claimed design.

1 Claim, 6 Drawing Sheets(56)
